UNITED STATES PATENT OFFICE

CHARLES STOLLBERG, OF NEW YORK, N. Y., ASSIGNOR TO AMERICAN CAN COMPANY, OF NEW YORK, N. Y., A CORPORATION OF NEW JERSEY

CONTAINER SEAM AND METHOD OF MAKING IT

Application filed May 16, 1927. Serial No. 191,612.

This invention relates in general to a container seam and the method of making it, and has more particular reference to the provision of an end seam between the bottom and the side wall of a can to form an outwardly projecting rolling ring for a can body.

A principal object of the invention is the provision of a bottom seam for a can body which projects to form a rolling ring and to protect the surface between the top and bottom seams which may be lithographed or provided with a printed label.

A further object of the invention is in the provision of a fluid-tight joint by incorporating therein a flexible tubular gasket which is collapsed between seamed flanges.

A further important object of the invention is in the formation of a seam with a tubular rubber gasket therein, in which the curled flange of the container end extends over the flange of the body and contacts with the outer wall of the body.

Numerous other objects and advantages of the invention will be apparent as it is better understood from the following description, which, taken in connection with the accompanying drawings, discloses a preferred embodiment thereof.

In the drawings:

Figure 1 is a side elevation of a complete container constructed in accordance with the principles of this invention;

Fig. 2 is a sectional detail view illustrating the relation of the parts before the seam is made; and

Fig. 3 is a similar detail illustrating the relation of the parts after the formation of the seam.

This invention comprises a can body 10 having a side seam 11 with its upper body edge outwardly crimped or rolled around a reinforcing wire to form a shoulder bead 12 adapted to engage clamping lugs 13 of a cover 14.

The bottom edge of the body 10 is first bent outwardly and then upwardly to form a flange 15, the outer wall of which is substantially parallel with the adjacent body wall.

The bottom 16, which is applied to the body 10, has a central inwardly dished por-

tion 17 with straight walls 18 adapted to engage closely the inner wall of the body 10 and with an outwardly extending flange 19 of which the edge 20 is turned upwardly to form a channel for receiving a flexible tubular gasket 21 of rubber or the like, the extreme edge of the flange 19 being rolled so as to curve slightly inward at the top.

The bottom is then pressed inwardly upon the rolled bottom edge of the body and the inwardly curled portion of the bottom flange is crimped over the upwardly turned straight part of the body flange in imitation of the top seam of the container, the inwardly turned edge 20 of the bottom flange engaging the outer wall of the can body, as shown more clearly in Fig. 3. The edge of the body flange 15 is thus crimped inwardly but preferably terminates at a slight distance from the outer wall of the body 10, and the rubber gasket 21 is compressed between the two flanges, forming a gasket which is thin at both compressed edges.

In crimping the bottom flange in place the adjacent straight wall 18 of the bottom and the contacting wall of the body 10 are inclined slightly outward, thus making a firm tight joint. The edge of the bottom flange 19 engages the outer wall of the body 10 opposite the contacting straight portions of the body 10 and bottom, and below the inwardly dished portion 17 of the bottom.

The bottom seam thus formed not only makes a fluid-tight joint but the seam projects from the surface of the outer body wall substantially the same distance as the top seam with the cover applied thereto, thereby providing a pair of rolling rings upon which the filled can body may be rolled and also protecting a label or a lithographed surface on the outer wall of the can body between the top and bottom seams.

In making the bottom seam, it is obvious that the flanged edge of the body and the flange of the bottom are partially formed and the gasket is applied to the channel of the bottom before the seaming operation is completed and when the bottom flange is crimped over the flexible gasket is compressed and collapsed between the flanges.

It is thought that this invention and many of its attendant advantages will be understood from the foregoing description, and it will be apparent that many changes may be 5 made in the form, construction and arrangement of the parts without departing from the spirit and scope of the invention or sacrificing all of its material advantages, the form hereinbefore described being merely a preferred embodiment thereof.

I claim:

The combination of a container body having a marginal edge bent outwardly and back along the main portion of said body to form 15 a tubular flange, an end closure having a central offset portion dimensioned to fit within said body, and having beyond said central portion a tubular flange at its edge containing the tubular flange of the body, said tubular flanges being eccentric to one another, and 20 a gasket member arranged between the bottom parts of said flanges, the marginal edges of the said flanges of said body and end closure being conjointly bent in substantially to 25 said body to compress said gasket and to form a hollow bead.

CHARLES STOLLBERG.
